(57) **CLAIM**

What is claimed is the chemical vapor deposition fixture, as shown and described.

DESCRIPTION

FIG. 1 shows a perspective view of the chemical vapor deposition fixture.

FIG. 2 shows a front view thereof;

FIG. 3 shows a rear view thereof;

FIG. 4 shows a first side view thereof;

FIG. 5 shows a second side view thereof; and,

FIG. 6 shows the bottom view thereof.

The broken line showing of parts of the drawings is included for the purpose of illustrating use and environment and forms no part of the claimed design.

1 Claim, 6 Drawing Sheets
